(57) **CLAIM**

The ornamental design for an applicator for a therapeutic device, as shown and described.

DESCRIPTION

FIG. 1 is a front, top perspective view of an embodiment of an applicator for an electromagnetic muscle stimulator therapeutic device;

FIG. 2 is a front side view of the applicator of FIG. 1;

FIG. 3 is a back side view of the applicator of FIG. 1;

FIG. 4 is a left side view of the applicator of FIG. 1, the right side view thereof being a mirror image;

FIG. 5 is a top plan view of the applicator of FIG. 1; and,

FIG. 6 is a bottom plan view of the applicator of FIG. 1.

The broken lines shown in the figures depict portions of the applicator for a therapeutic device and form no part of the claimed design.
